UNITED STATES PATENT OFFICE.

JUSTUS R. KINNEY, OF JAMAICA PLAIN, MASSACHUSETTS.

RELIEF VALVE FOR ROTARY PUMPS.

Application filed June 5, 1926. Serial No. 113,873.

This invention relates to relief valves for rotary pumps and particularly to rotary vacuum pumps by which it is desired to create a perfect vacuum in any desired enclosure.

The object of the invention is to so construct and locate the relief valve in the head of a pump that the valve will be fully closed before the piston of the pump passes it, thereby preventing any air forced into the valved outlet from escaping into the piston chamber as soon as the piston passes this outlet.

This object is attained by the mechanism illustrated in the accompanying drawing.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a vertical section of a pump embodying the principles of the present invention.

Figure 2 represents a section on line 2, 2, on Fig. 1 showing the main discharge from the pump, and

Figure 3 represents a section on line 3, 3 on Fig. 1 and showing the relief valve closed.

Similar characters indicate like parts throughout the several figures of the drawing.

In the drawings, 10 is a casing having extending laterally therethrough a cylindrical chamber 11 and a compartment 12 located above the chamber 11 and communicating therewith by means of a semi-cylindrical passage 13.

The casing 10 has secured to its opposite ends closing plates 14, 15 in which is disposed a rotatable shaft 17.

An inlet pipe 19 communicates with the upper end of the compartment 12.

The shaft 17 extends through the center of the chamber 11 and has keyed thereto a cam member 20 which is surrounded by an annular piston 21 having a laterally extend-

ing blade 22 which extends through a slot formed in an oscillating pin 23 disposed in and fitting the passage 13.

The shaft 17 extends through the cam member 20 at one side of its center forming an eccentric, thereby causing the piston 21 to contact at one point with the cylindrical wall of the chamber 11 during the entire rotation of the shaft 17.

The blade 22 has a pocket 24 extending inwardly from its outer end, one wall 25 of which is provided with the port 26 through which gas is admitted to the chamber 11 from compartment 12 at stated times during the rotation of the shaft 17.

The lower end of the port 26 is considerably removed from the periphery of the piston so that during a part of the revolution of the piston 21 the said port 26 is closed and no gas can pass through the same.

The slotted blade-receiving pin 23 extends beyond the ends of the casing 10 with cylindrical ends disposed in cylindrical recesses formed in the end closing plates 14, 15, all as shown in my application Ser. No. 101,932, filed April 14, 1926, and on which the present invention is an improvement.

The lower side of the pin 23 has a flat face as indicated at 31.

The cam member 20 is preferably cored out with openings at the ends in which are disposed closing plugs 32.

Closely adjacent one side of the passage 13 on the discharge side of the pump, the casing 10 is provided with a plurality of discharge ports 33 extending into a pocket 34, the opposite ends of which have narrow extensions 35 in which are positioned the opposite ends of the valve 36 of thin spring metal.

This valve 36 normally closes the ports 33 and has superimposed thereon a follower 37 forced downwardly by a spring 38, the curved upper portions of which bear against a rib 39 forming a part of the discharge nozzle 40.

As will be noted in Fig. 1 this rib 39 is narrower than the passage 41 extending from the bottom of said nozzle.

The lower face of the follower 37 has a plurality of cross ribs 42 which bear on the valve 36 leaving space between these ribs through which the gas may freely pass.

During the operation of the pump the shaft 17 rotates in the direction of arrow a

on Fig. 1, and when the piston 21 is in the position shown in said Fig. 1 both the inlet 26 and outlet 33 from the chamber 11 are closed.

5 As the piston 21 commences to revolve in direction of arrow *a* all gas in advance of said piston will be forced toward the outlet ports 33 and through said ports into the discharge nozzle 40.

10 During this forward movement the blade 22 will commence to tilt, moving the slotted pin 23 about its axis and as the piston continues to move forward said blade 22 will commence to move downwardly until the 15 piston reaches a position *c* in which the lower end of the port 26 will register with the flat face 31 of the slotted pin 23.

Further rotation of the piston will uncover the port 26 and permit gas to be drawn 20 from the pockets 24 into the chamber 11 where it will be forced ahead of the piston to the discharge outlet ports 33, in the next cycle of the piston.

The port 26 will remain open until the 25 piston 21 reaches a position *b* in which the port 26 will be closed and remain closed until the piston again reaches the position in which the lower end of port 26 registers with the flat face 31.

30 While the contacting point of the piston 21 is traveling from *b* to *c* the supply of gas to the chamber 11 is entirely cut off and as the piston continues to rotate in the direction of arrow *a* the gas in advance of said 35 piston 21 will be compressed, this increased pressure forcing the valve plate 36 from its seat and permitting the gas to be discharged through the openings 33 into the pocket 34 and then through the outlet 40.

40 When the last of the gas in advance of the piston is about to be forced through the openings 33, the port 26 will be closed and no new supply of gas will be admitted until the piston attains the position *c*.

45 The cam 20 is slightly shorter than the space between the inner faces of the end plates 14, 15 and consequently any lubricant admitted to the chamber 11 forms a film at each end of the cam 20, said lubricant passing from one end to the other through the 50 grooves 51.

This film of lubricant also enters recesses in the ends of the piston 21 and flows into oil grooves at the opposite ends of the blade 55 22, as described in my copending application.

The grooves in the blade 22 do not extend to the outer end thereof and therefore the oil in these grooves cannot escape therefrom.

It is obvious, therefore, that all the moving 60 parts of the pump will be thoroughly lubricated by the lubricant admitted to the chamber 11 and the amount of oil or lubricant can be regulated by means of a needle valve, as shown in said copending application.

To the outlet side of the casing 10 is secured a housing 56 having a chamber 57 therein communicating with the main chamber 11 by a cone-shaped opening 58 to which the valve 59 is fitted. This opening 58 is 70 formed in an end plate 15.

The valve 59 has a stem 60, the end of which extends into a cylindrical pocket 61 which serves as a guide for said stem 60 when the valve 59 is forced from its seat.

A spring 62 normally retains the valve on its seat and may be compressed when the pressure of gas within the main chamber 11 reaches a predetermined limit.

The pocket 61 is formed in a member 70 threaded to the end of the housing 56, the outer end of said member 70 being flat-sided as at 71, providing a means whereby said member 70 may be adjusted to vary the tension of the spring 62.

At any low pressure the opening 58 is closed and there is no escape for the gas therethrough.

From the housing 56 extends a pipe 63, the other end of which communicates with the compartment 12.

The object of this by-pass 63 is to make the pump run more easily when it is first operated, thereby greatly reducing the power required of the motor which actuates the 95 driving shaft 17.

When the pump is first actuated the chamber 11 is filled with gas under atmospheric pressure and this pressure offers considerable resistance to the rotation of the piston 21.

By providing the by-pass 63 this gas in advance of the rotating piston will pass through the by-pass into the compartment 12 until the contacting point on the piston passes the opening 58 from which point the gas in advance of the piston will be forced from the chamber 11 through the openings 33, the spring 38 yielding sufficiently to permit free discharge of the gas.

As only a portion of the gas in the chamber passes through the pipe 63 and the remainder passes through the discharge openings 33 and escapes, the pressure in the chamber 11 will be gradually decreased to a point where it will be insufficient to move the valve 59 from its seat.

When this limit has been reached the gas remaining in the chamber will all be discharged through the openings 33 until a perfect vacuum is created in the chamber 11, and at this time very little power is required to rotate the piston 21, as there remains in the chamber no gas to retard its movement.

When the gas escapes through the openings 33 with some little pressure the valve 36 may be lifted from its seat above the openings 33, but when this pressure decreases so that it is insufficient to offset the tension of spring 38, the pressure will cause the thin flexible valve 36 to curve slightly between

the ribs 42 and pass noiselessly into the pocket 34 and thence through the outlet 40, 41.

It will be noted that normally the inner 5 end of the valve 59 is flush with the inner face of the end plate 15 which is of considerable importance in the operation of the pump.

Heretofore the entrance 58 to the by-pass 10 63 was located in the cylindrical wall of the chamber 11 and at an abnormal pressure the valve 59 would be opened as the piston 21 advanced towards said entrance and considerable gas would enter the entrance 58 15 and before the valve could close the contacting point of the piston 21 would pass the entrance 58.

This would permit the gas thus collected in the entrance to escape into the chamber 20 11 behind the piston 21 as it continued to advance.

As a consequence it was found difficult to create an absolutely perfect vacuum which is the particular object desired to be 25 attained.

The desired result is achieved, however, by locating the entrance 58 to the by-pass in the end wall of the chamber 11 as by so locating the relief valve opposite a broad 30 end face of the piston, the valve 59 is given time to entirely close with its inner end flush with the inner face of the end wall 15 before the piston 21 commences to uncover the entrance 58. Consequently no gas entering 35 the entrance 58 can escape back into the chamber as it is wholly covered by piston 21 until the valve 59 is again closed.

This is of the greatest importance as by 40 thus locating the relief valve the pump may be operated to quickly create a perfect vacuum in any enclosure.

This makes a most effective vacuum pump 45 which will be noiseless in operation and which requires very little power to actuate it.

It is believed that the operation and many advantages of the invention will be understood without further description.

Having thus described my invention, I 50 claim—

1. In a device of the class described, a casting having a cylindrical piston chamber therein provided with an inlet thereto and an outlet therefrom; a piston revoluble

therein and contacting at one point with 55 the cylindrical wall of said chamber, the ends of said piston contacting with the end walls of said chamber; a by-pass communicating with an opening in the wall at one end of said piston chamber; and a valve 60 closing said by-pass and adapted to be opened when the pressure within said chamber exceeds a predetermined limit.

2. In a device of the class described, a casing having a cylindrical piston chamber 65 therein provided with an inlet thereto and an outlet therefrom; a piston revoluble therein and contacting at one point with the cylindrical wall of said chamber, the ends of said piston contacting with the end 70 walls of said chamber; a by-pass from one end of said piston chamber; and a valve closing said by-pass and adapted to be opened when the pressure within said chamber exceeds a predetermined limit, the inner 75 end of said valve when closed being flush with said end wall.

3. In a device of the class described, a casing having a cylindrical piston chamber 80 therein provided with an inlet thereto and an outlet therefrom; a piston revoluble therein and contacting at one point with the cylindrical wall of said chamber, the ends of said piston contacting with the end 85 walls of said chamber; a by-pass communicating with an opening in the wall at one end of said piston chamber and considerably removed from the outlet from said chamber; and a valve closing said by-pass and adapted to be opened when the pressure within said 90 chamber exceeds a predetermined limit.

4. In a device of the class described, a casting having a cylindrical piston chamber therein provided with an inlet thereto and an outlet therefrom; a piston revoluble 95 therein and contacting at one point with the cylindrical wall of said chamber; a by-pass from the outlet side of said chamber to the inlet side thereof; and a valve in the entrance to said by-pass adapted to be opened as the piston approaches said entrance and the pressure within the chamber exceeds a predetermined limit and is adapted to be fully closed before the piston uncovers said entrance.

Signed by me at 746 Old South Bldg., Boston Mass., this 4th day of June, 1926.

JUSTUS R. KINNEY.
